UNITED STATES PATENT OFFICE

91,887

DESIGN FOR A COASTER WAGON WHEEL

Leland G. Knapp, Chicago, Ill., assignor to Montgomery Ward & Co., Incorporated, Chicago, Ill., a corporation of Illinois

Application May 4, 1933, Serial No. 48,004

Term of patent 7 years

To all whom it may concern:

Be it known that I, LELAND G. KNAPP, a citizen of the United States, residing at Chicago, in the county of Cook, and State of Illinois, have invented a new, original, and ornamental Design for a Coaster Wagon Wheel, of which the following is a specification; reference being had to the accompanying drawing, forming a part hereof.

In the drawing,

Fig. 1 is a side elevation of a coaster wagon wheel embodying the present design; and

Fig. 2 is a vertical transverse sectional view thereof on the line 2—2, Fig. 1.

The salient features of the design includes ornamentation of the wheel and particularly the rim portion thereof in such a manner as to produce in a small coaster wagon wheel the effect of a wheel having a large balloon tire thereon.

I claim:

The ornamental design for a coaster wagon wheel, as shown and described.

LELAND G. KNAPP.
